UNITED STATES PATENT OFFICE.

JONAS H. CROWSON, OF LINDEN, TEXAS.

FISH-TRAP.

No. 832,778

Specification of Letters Patent.

Patented Oct. 9, 1906.

Application filed June 2, 1906. Serial No. 319,865.

To all whom it may concern:

Be it known that I, JONAS H. CROWSON, a citizen of the United States, residing at Linden, in the county of Cass and State of Texas, have invented a new and useful Fish-Trap, of which the following is a specification.

This invention relates to fish-traps; and its object is to provide a very simple and inexpensive device of this character formed of very few parts and which constitutes an effective means for trapping fish.

The invention consists of a main compartment formed of a length of wire fabric bent upon itself and having the space between its edges closed by fabric strips, which also serve to close the ends of a front compartment, which is likewise formed in a single length of fabric folded upon itself, the ends of said fabric being bent inward to constitute an inlet, while the opposite portion of the fabric forming the front compartment projects between and is secured to the end of the fabric of the main compartment and is cut transversely to form an opening through which fish can enter the main compartment.

The invention also consists of certain other novel features of construction and combinations of parts, which will be hereinafter more fully described, and pointed out in the claims.

In the accompanying drawings is shown the preferred form of the invention.

In said drawings, Figure 1 is a longitudinal section through the trap; and Fig. 2 is a perspective view, the greater portion of the mesh being removed, but the edge wires of the fabric strips being shown in proper positions.

Referring to the figures by numerals of reference, 1 is a length of wire fabric, such as ordinarily employed for fencing purposes, and this fabric is folded upon itself to form a rounded end, while the ends of the fabric 1 are twisted into engagement with opposite portions of another length of wire fabric 2, which is folded on itself and projects between the ends of the fabric 1. That portion of the fabric 2 which projects into the folded fabric 1 is cut between the sides, leaving the wires of the fabric unsevered close to the sides thereof. The wires which are severed in this manner constitute prongs 3, which project into the compartment 4, formed by the length of fabric 1. The ends of the fabric 2 are bent inward, and the wires of said fabric constitute prongs 5, which project into the compartment 6, formed by the fabric 2.

The ends of the two compartments 4 and 6 are closed by two strips of wire fabric 7 and 8, which are cut to conform to the contour of the ends of the compartments, and the wires of these strips are twisted into engagement with the edge wires of the fabrics 1 and 2, so as to constitute efficient closures for the compartment. The end strip 8 is not fastened throughout its edges to the fabric 1, but instead engages a binding-wire 9 at its rear end, and that portion of the strip 8 secured to this binding-wire constitutes a door or closure which may be swung open so as to permit an arm to be inserted into the compartment 4 for the purpose of removing fish therefrom. The door is adapted to be held in closed position by means of a spring-catch 10, adapted to engage the end portion of the compartment 4.

In using this trap suitable bait is placed on the prongs 5 and the device is lowered into the water in any suitable manner so as to rest upon the bed. Fish will be attracted to the bait and will nibble at it and finally work between the prongs 5, which will prevent them from passing from compartment 6 between said prongs. In the efforts of the fish to escape they will pass between the prongs 3 and into the compartment 4, from which it will be impossible for them to escape. They can be removed from this main compartment by opening the closure at the rear end thereof.

It is to be noted that the entire trap is formed of ordinary wire-netting and that but four of these strips are employed—to wit, two strips for forming the two compartments and two end strips. The device can therefore be constructed at comparatively slight cost, and as it is made of very few parts there is nothing to get out of order and the trap is always set.

What is claimed is—

1. A trap formed of wire fabric and comprising a length of fabric folded upon itself and having inturned ends constituting prongs, that portion of the fabric opposite said prongs being cut to constitute prongs, another length of fabric secured to the pronged fabric at opposite sides of the cut portion thereof, and end strips secured to the edges of the lengths of fabric.

2. A trap formed of wire fabric and comprising a length of fabric bent upon itself and having inturned ends constituting prongs, that portion of said fabric opposite the prongs being cut to form a plurality of prongs,

a length of fabric secured to the first-mentioned fabric at opposite sides of the cut portion therein, end strips secured to the edges of the fabric, a binding device for one of said strips, said device and strip constituting a closure.

3. A trap formed of wire fabric and comprising a length of fabric bent upon itself and having inturned ends constituting prongs, 10 that portion of said fabric opposite the prongs being cut to form a plurality of prongs, a length of fabric secured to the first-mentioned fabric at opposite sides of the cut portion therein, end strips secured to the edges 15 of the fabric, a binding device upon one of said strips, said device and strip constituting a closure, and means for locking the closure.

4. A trap formed of metal fabric and comprising a length of fabric folded upon itself to 20 form a main compartment, another length of fabric folded upon itself to constitute a front compartment, the fabric of said front compartment extending between and secured to the ends of the fabric of the rear compartment, the ends of the fabric of the front compartment being inturned to constitute bait-receiving prongs, that portion of said fabric 25 projecting into the front compartment being cut to produce a plurality of prongs, and end strips secured over the ends of the two compartments, one of said strips having a free end, a binding device secured to said free end, and means for fastening said device to the fabric of the main compartment, said binding device and the adjoining portion of the end fabric constituting a closure.

strips secured over the ends of the two compartments.

5. A trap formed of metal fabric and comprising a length of fabric folded upon itself to form a main compartment, another length of fabric folded upon itself to constitute a front compartment, the fabric of said front compartment extending between and secured to the ends of the fabric of the rear compartment, the ends of the fabric of the front compartment being inturned to constitute bait-receiving prongs, that portion of said fabric projecting into the front compartment being cut to produce a plurality of prongs, end strips secured over the ends of the two compartments, one of said strips having a free end, a binding device secured to said free end, and means for fastening said device to the fabric of the main compartment, said binding device and the adjoining portion of the end fabric constituting a closure.

In testimony that I claim the foregoing as my own I have hereto affixed my signature in the presence of two witnesses.

JONAS H. CROWSON.
